A. A. MARTELL,
EXPANSIBLE TOOL,
APPLICATION FILED APR. 21, 1915.

1,201,845.

Patented Oct. 17, 1916.

UNITED STATES PATENT OFFICE.

ALBERT A. MARTELL, OF MANSFIELD, MASSACHUSETTS.

EXPANSIBLE TOOL.

1,201,845.

Specification of Letters Patent.

Patented Oct. 17, 1916.

Application filed April 21, 1915. Serial No. 22,933.

To all whom it may concern:

Be it known that I, ALBERT A. MARTELL, of Mansfield, in the county of Bristol and State of Massachusetts, have invented a new and useful Expansible Tool, of which the following is a specification.

The general object of my invention is to increase the efficiency and accuracy of expansible tools.

10 One particular object of my invention is to provide an expansible tool such, for example, as a reamer, with means to prevent bulging of the blades.

Another object is to provide means for 15 burnishing the cut surfaces.

Another object is to provide the tool with a rear guide to be used with different sizes of cut surfaces.

Other objects will be pointed out below.

20 My invention consists partly in means for bending the ends of the blades inwardly, partly in rounding an edge of the blades and partly in a sleeve with an exterior of different sizes and partly in other features described below.

25 In the drawings: Figure 1 is a central longitudinal sectional view of a tool embodying my invention; Fig. 2 is a central longitudinal sectional view of the body of the tool shown in Fig. 1; Fig. 3 is a section on line 3—3 of Fig. 1; Fig. 4 is a perspective view of one of the blades; and Fig. 5 is a detail illustrating the principle of construction and operation.

30 By way of example I disclose an expansible tool in the form of a reamer. The body or shank A has enlarged portion A' provided with longitudinal recesses A² to receive the blades. Threaded portions a and 35 a' are provided to cooperate with the clamping nuts and at one end the shank is internally threaded at a² to cooperate with any suitable pilot. The shank is also provided with circular holes a³ in line with recesses A².

40 Each blade B is provided with engaging surfaces b, b', b² and with the cutting edge b³ and the rounded edge b⁴ whose function is to burnish the surface which has been cut. This rounded edge is so located that

45 it will properly engage the cut surface and I preferably have it extend from the rear end of the blade about as far as shown in the drawing. Wedges d, d', d² are provided, each comprising a circular portion to enter

the appropriate hole a³ and a cam surface 55 to engage the appropriate engaging surface b, b' or b² on the blade.

An important purpose of my invention is to prevent bulging of the blades at the center and this I accomplish by having the 60 blade engage the middle wedge such as d', and then screwing up the clamping nuts E and F so that the ends of the blade are forced inwardly with the result that the 65 blade is held tightly against the center wedge with no possibility of outward or inward bulging. When the blade has been so adjusted its cutting and burnishing edges are ground off to be parallel with the longitudinal axis of the tool. The bending inward of the ends of the blade is due in the 70 form shown to the fact that the plane of the cam surface b² is nearer to the plane of the cam surface b' than is the plane of the cam surface b. The peculiar relative arrangement of cam surfaces might be had, 75 for the set of cam surfaces on the wedges, but I have illustrated the arrangement for the set of cam surfaces on the blade.

Another important feature of my invention is the rear circular guide G which is provided with four portions g, g', g² and g³ whose sectional dimensions vary to suit different sizes of cutting diameter of the tool. In the drawing the portion g is of the smallest dimension, the next larger being portion g', then portion g² and then portion g³, but I prefer to have portion g² in the location shown as this is more convenient and it will be clear that if desired the portion g 80 may be innermost or if desired the guide may be slid off the shank and reversed so that portion g³ is innermost. In this way I provide a suitable guide for the tool during the latter part of its cutting action. 85

I do not claim the guide sleeve as such in this application as I intend to make it the subject of another application.

I do not claim the burnishing feature in this application as I intend to make that 100 the subject of another application.

What I claim is:

1. An expansible tool comprising a body provided with three engaging portions; a blade having three engaging portions corresponding to the engaging portions of the body to engage said portions of the body; and means to adjustably clamp said blade 105

to said body with all of the engaging portions of the latter in engagement with all of the engaging portions of the blade.

2. An expandible tool comprising a body formed with a plurality of longitudinal blade reserving slots; a blade mounted in each slot made with a cam surface near each end and with an intermediate cam surface; blade clamping means adjustably mounted on said body for engaging the end of the blades; and three parallel cam surfaces in each body slot two of which co-operate with the end cam surfaces of the blade of said slot and the other coöperating with the intermediate cam surface of the blade so that the blade clamping means bends the ends of each blade inward when tightened on to the latter.

3. An expandible tool comprising a body provided with three engaging portions; a blade having three engaging portions corresponding to the engaging portions of the body to engage said portions of the body; and means to clamp said blade to said body with said portions of the latter engaging said portions of all the former, the cutting edge of the blade being parallel to the longitudinal axis of the tool and said clamping means adapted to adjust said blade bodily transversely of said body.

4. An expandible tool comprising a body formed with a plurality of longitudinal blade receiving slots; blade clamping means

adjustably mounted on said body for engaging the ends of the blades; and a blade 35 mounted in each slot made with a cam surface near each end and with an intermediate cam surface the plane of the intermediate cam surface being nearer the plane of one end cam surface than the plane of the other 40 end cam surface.

5. An expandible tool comprising a body provided with two end engaging portions and an intermediate engaging portion; a blade provided with an intermediate, and 45 two end, engaging portions to engage said portions of the body; and means to adjustably clamp said blade to said body with said intermediate portion in engagement with the corresponding engaging portion of 50 the body.

6. An expandible tool comprising a body provided with three engaging portions; a blade having three engaging portions corresponding to the engaging portions of the body to engage said portions of the body, one of said portions of the blade, when the latter is unclamped, being out of engagement with the corresponding portion of the body; and clamping means to spring said one portion into engagement with the corresponding portion on the body and to retain all said portions of the body in engagement with all said corresponding portions of the blade.

ALBERT A. MARTELL.
